(57) **CLAIM**

The ornamental design for a separable combination flashlight-tool, as shown and described.

DESCRIPTION

FIG. 1 is a perspective view of the separable combination flashlight-tool in a partially unfolded configuration.

FIG. 2 is an another perspective view thereof.

FIG. 3 is a top view thereof.

FIG. 4 is a side view thereof.

FIG. 5 is a front view thereof.

FIG. 6 is a rear view thereof.

FIG. 7 is a bottom view thereof.

FIG. 8 is a third perspective view thereof in a folded configuration.

FIG. 9 is a top view thereof.

FIG. 10 is a side view thereof.

FIG. 11 is a bottom view thereof.

FIG. 12 is a fourth perspective view of the flashlight-tool apparatus in a partially unfolded configuration with the upper section separated from the lower section; and,

FIG. 13 is a side view thereof.

The broken line showing of the other parts are for illustrative purposes only and forms no part of the claimed design.
